CLAIM

The ornamental design for an exterior surface configuration of an automobile, as shown and described.

DESCRIPTION

FIG. 1 is a front, left side perspective view of an exterior

surface configuration of an automobile according to my novel design, with the top up;

FIG. 2 is a front, left side perspective view of an exterior surface configuration of an automobile according to my novel design, with the top down;

FIG. 3 is a left side view of an exterior surface configuration of an automobile according to my novel design, with the top up;

FIG. 4 is a left side view of an exterior surface configuration of an automobile according to my novel design, with the top up;

FIG. 5 is a right side view of an exterior surface configuration of an automobile according to my novel design, with the top up;

FIG. 6 is a rear, left side perspective view of an exterior surface configuration of an automobile according to my novel design, with the top up;

FIG. 7 is a front view of an exterior surface configuration of an automobile according to my novel design, with the top up;

FIG. 8 is a rear view of an exterior surface configuration of an automobile according to my novel design, with the top up; and,

FIG. 9 is a top plan view of an exterior surface configuration of an automobile according to my novel design.

The broken line drawings of the wheels, license plate holders, side view mirrors, rear view mirror, interior dashboard, and interior seating in all figure views are for illustrative purposes only and form no part of the claimed design.
